UNITED STATES PATENT OFFICE.

ARTHUR PENTECOST, OF EAST ORANGE, NEW JERSEY, ASSIGNOR TO THE ADDER MACHINE COMPANY, OF WILKES-BARRE, PENNSYLVANIA, A CORPORATION OF PENNSYLVANIA.

CALCULATING-MACHINE.

1,282,282.

Specification of Letters Patent.

Patented Oct. 22, 1918.

Application filed March 10, 1916. Serial No. 83,236.

To all whom it may concern:

Be it known that I, ARTHUR PENTECOST, a subject of the King of England, residing at East Orange, Essex county, New Jersey, have invented new and useful Improvements in Calculating-Machines, of which the following is a specification.

This invention relates more particularly to means for non-printing in one or more denominational places, in a column, and while it may be variously applied, one field of its usefulness is found in the so-called statement calculating machines, of the key-set, crank-operated type, which form I have selected as an illustration of one embodiment of the invention.

The principal object is to provide automatic means effective without attention on the operator's part, to non-print in one or more denominations intermediate other denominations in which the printing of characters occurs, although the invention may be arranged to prevent printing in any denomination regardless of its location.

In the particular form shown, the invention is designed to permit the printing of numerals, including ciphers, to indicate any day of the month, and prevent the printing of characters in that denomination wherein the units digits of the day of the month are printed, when special designation keys in the denomination reserved for the tens digits of the day of the month, are operated.

A further object is to enable keys located in one denomination, to control the printing of characters in one or more different denominations of the keyboard, such control being exercised automatically and without thought on the part of the operator other than to depress the key corresponding to the indication which he desires shall be printed.

To this end, I have provided keys in one denomination of a keyboard, the operation of which not only sets mechanism to effect an imprint of the indications corresponding to such keys, but in addition, automatically eliminates the printing in one or more different denominations, thus to enable the operator to control at will, from the keys of one denomination, the printing of characters

in a different denomination or denominations.

In the form of my invention, herein illustrated, special designations as "Bal", "Net" or "3%" are printed in the denomination corresponding with the tens digits of the day of the month, without the succeeding cipher, in the denomination corresponding with that in which the units digits of the day of the month are printed, which cipher would be useless and confusing when printing such special designations.

To these and other ends, the invention includes certain novel features and combinations of parts, all of which will be more fully set forth hereinafter and particularly pointed out in the claims.

In the accompanying drawings, Figure 1 is a longitudinal sectional view through the well-known Wales calculating machine, equipped with one embodiment of the invention;

Fig. 2 is an enlarged detail sectional view of the printing mechanism, showing the means for non-printing or eliminating the printing in a denomination;

Fig. 3 is a detail perspective view of such non-printing mechanism, removed from the machine, and

Fig. 4 is a reduced plan view of a part of the keyboard.

Although the invention is applicable to other machines, I have shown it in connection with the Wales calculating machine, and for a more complete disclosure of the usual form of Wales machine, reference is hereby made to U. S. patents to Wales, #745,539, December 1, 1903; #768,097, August 23, 1904; #794,205, July 11, 1905; and #797,032, August 15, 1905, and the pending application of Charles V. Wilgus, filed April 22, 1912, Serial No. 692,242.

This machine includes a base 965, Fig. 1, supporting side frames 967, between which are located the keyboard or selective mechanism, the accumulating section, and the printer section.

The keys are arranged in rows or denominations 190, 190^a, 190^b, 190^c, (Fig. 4) on the keyboard according to the decimal or other

system, there being generally, a counter or accumulating wheel 490 with its rack or positioning bar 310, a type carrier 514, and hammer mechanism for each denominational row of keys. The type carriers occupy denominational positions corresponding with the respective rows of keys which control the carriers. The operation of the various denominational trains of mechanism are alike, and an explanation of one will suffice for all.

Depression of a key 190^b (Fig. 1) and key stem 117, rocks a lever 116 to project an index pin or stop 115 into the path of a corresponding positioning bar or rack 310. A rack detent 221 normally lying in the path of the rack 310 to arrest the latter when no keys in that row or denomination are depressed, is displaced by the stop 115 of the operated key.

Front and rear arms 312 and 311 journaled, respectively, on the cross shaft 300 and cross rod 301 mounted in the side frames 967, pivotally support the racks or positioning bars 310 at 361 3/4 and 350 for back and forth travel. Springs 383 connected to the rear supporting arms 311, and to a restraining and restoring bail 205 supported in the path of the front supporting arms 312, by rocking fingers 265, tend to advance the racks, which advance is normally prevented by the bail 205.

Turning the main drive shaft 200 on its forward stroke, rocks a crank 210^a to cause a roll 241 mounted thereon, to traverse a cam slot 220^a in a cam arm 220 pivoted at 260 1/2 to the side frames 967, swinging the cam arm forwardly. The cam arm is fixed to the casting carrying the fingers 265 and bail 205, and withdraws the fingers and bail from contact with the front supporting arms 312. The bail, on its withdrawal, further tensions the springs 383, which advance the racks or positioning bars 310 until the latter are arrested by contact with the projected stop 115 or with the rack detents 221 in those denominations in which no key is depressed.

During the advance of the racks, the counters 490 with their pinions 435 remain out of mesh with the racks.

Converging levers 311^a, projecting rearwardly from the rear rack-supporting arms 311, are connected by links 515 1/8 with the stems of type carriers 514 arranged in a row across the machine and guided between plates 527 1/4 and 527 1/2. As the positioning bars or racks 310 advance under the influence of their springs 383, the rear supporting arms 311 and converging levers 311^a swing upwardly to lift the type carriers and bring the types 561 mounted in the type carriers, successively to the printing line on the platen 2094. The arrest of the racks by the projected stops 115 positions the types cor-

responding to the keys depressed, at the 65 printing line.

A universal detainer 518 secured to a shaft 502, normally restrains a series of printing hammers 510 3/8 journaled on a cross shaft 500, against the tension of their springs 580, 70 extending between the respective hammers and a tensioning bail 505 1/2 mounted in swinging arms 512 1/4 fast on a tensioning shaft 502 1/4.

Individual hammer latches 518 1/4 journaled on a cross bar 504, are engaged by their springs 581, with lugs 510 3/8^a on the hammers 510 3/8 to lock the hammers against operation when released by the universal detainer 518.

The converging levers 311^a in those denominations wherein keys have been depressed, when swinging upwardly, release trip bars 520 3/4 normally held in idle position against the tension of their springs 583, by the contact of the converging levers with ears 520 3/4^a on the trip bars. The trip bars, when released, follow the converging levers upwardly, and strike the corresponding individual latches 518 1/4 to disengage the latter from their hammers 510 3/8, prior to the release of the detainer 518, which is effected by mechanism (not shown), near the end of the forward stroke. Mechanism, also not shown, rocks the tensioning shaft 502 1/4 95 and arms 512 1/4 to tension the hammer-driving springs 580 on the forward stroke of the main drive shaft 200, and upon the release of the detainer 518, the springs 580 drive such of the hammers 510 3/8 as have 100 been freed from their individual latches 518 1/4, against the firing pins or plungers 562 1/4, which in turn strike the ends of those types 561 positioned at the printing line, to effect an imprint on the work sheet 105 carried by the platen.

After the racks 310 have advanced to their predetermined positions and about the time when the printing takes place, the counters 490 and pinions 435 drop into engagement 110 with the racks, through the action of the usual Wales mechanism, not shown.

The main drive shaft 200 on its forward stroke, has tensioned the main restoring spring 285, which, upon the release of the 115 main drive shaft, after it has reached the limit of its forward travel, returns the parts to their normal positions of rest. The crank 210^a reversely traverses the cam slot 220^a in the cam arm 220 to force the restraining and 120 restoring bail 265, 205 against the advanced forward supporting arms 312 to retire the racks 310 to their normal positions. The racks, during such retirement, turn the counters 490 through pinions 435, to register thereon, amounts corresponding to the 125 values of the depressed keys.

The retirement of the racks 310 returns

the converging levers 311^a and type carriers 514 to normal. The levers, in their travel, contact the lips 520 3/4^a on the trip bars 520 3/4 to depress the bars against the tension 5 of their springs 583, and permit the springs 581 to return the individual hammer latches to effective position.

At the end of the return stroke, the counters 490 and pinions 435 are disengaged from 10 the racks and resume the positions shown in Fig. 1.

The shaft 500 on which the hammers are journaled, carries arms 519 which support a hammer-resetting bail 509 1/2 lying behind 15 and in contact with the hammers. On the forward stroke of the main drive shaft, the shaft 500 is turned (by the usual Wales mechanism, not shown) to withdraw the resetting bail out of the path of travel of the hammers. On the return stroke, the shaft 500 is 20 reversely turned to press the bail against the hammers and restore them to, and hold them in normal position. The detainer 518 is returned to effective position over the hammers after the latter have been reset, and 25 holds them in such position during the withdrawal of the resetting bail on the next forward stroke.

The individual hammer latches 518 1/4 30 are provided with the usual cross-over tails or release fingers (not shown), whereby to print ciphers to the right of any significant digit, except in the units denomination.

In statement machines, such as the one 35 herein shown, it is customary to provide a manually-controlled split and normal mechanism generally comprising a key, not shown, the depression of which operates a slide 515 3/4 mounted in brackets 516 3/4, 40 and slotted to accommodate one or more of the tails or release fingers 518 1/2 projecting from the individual latches 518 1/4. The fingers which enter the slots in the slide 515 3/4 are pivoted, as at 554 1/2, to their 45 latches, instead of being fixedly secured thereto, as is usual when no split in the printer section is provided.

Depression of the key operates the slide 515 3/4 to swing the pivoted fingers 518 1/2 50 from beneath the adjacent latches to the left, so as to prevent the release of the denominational latches bearing the pivoted fingers, when a significant digit of higher denomination is to be printed, and thus interrupts 55 the printing of ciphers to the right of such digit of higher denomination.

The statement keyboard in the present embodiment of the invention comprises a plurality of rows of numeral keys 190 60 (Fig. 4) arranged in denominations, one such row only being shown. To the left of these rows of keys is another row of numeral keys 190^a which, when the split is not effective, forms a part of the regular denomina-

national series of keys. When the split is 65 effective, however, this row of keys 190^a is used to print the units digits of the days of the month.

To the left of the row of keys 190^a is another row of keys 190^b comprising numeral 70 keys from 1 to 3 to print the tens digits of the days of the month, the remaining keys either bearing special designations as "Bal", "Net", "3%" and the like, or, where less than six special designations are required, the 75 keys intermediate the "3" and the lowest special key, may bear the successive numerals "4", "5" and "6", as illustrated. It will be noted that the keys bearing special designations occupy the same positions as the numeral keys "7", "8" and "9" of the other rows and may be used to register those digits on the counter 490 corresponding with the denominational row of keys 190^b. The type carrier coacting with this row carries types 80 corresponding to the special designations, so that the abbreviations "Bal", "Net" and "3%" will be printed instead of the figures "7", "8" and "9".

The adjacent row of nine keys 190^c to the 90 left of row 190^b, bears abbreviations of the months from "Jan" to "Sep", a short additional row of three keys 190^d bearing abbreviations of the remaining months "Oct" to "Dec". The rows of keys 190^c and 190^d 95 control the excursions of a positioning bar 310 common to both, to adjust a single type-carrier bearing corresponding types, relatively to the printing line. A counter 490 could readily be associated with this positioning bar, but it is not customary.

The foregoing is old and constitutes a part 100 of the present invention only in so far as it is combined with the novel features now to be set forth.

As the line of split is located between the rows or denominations of keys 190 and 190^a, to interrupt cipher printing to the right of row 190^a, it is obvious that when the split 110 is effective, the cipher to the right of the tens digit of the date will print, as

"Jan 10 132.84"

without printing a line of ciphers between the cipher in the units place of the day of the month and the digit of highest value in the 115 amount.

It often happens, however, that the operator desires to print one of the special designations, as

"Bal 475.98"

The special designation keys being located 120 in the second row 190^b to the left of the split, a cipher would ordinarily be printed directly to the right of the special designation, or in the units place of the day of the 125 month, to prevent which, I have contrived a means which enables the printing of numerals, including a cipher, in the denomination

corresponding with row 190^a to the left of the split when a numeral key in row 190^b is depressed, and which prevents the printing of any character in the denomination corresponding to row 190^a when a special designation key in row 190^b is depressed, even though a key in denomination 190^a is also operated.

To accomplish this result, means, which becomes effective after the rack has reached a predetermined point in its travel, locks the printing hammer 510 3/8 of the denomination 190^a immediately to the left of the split, out of operation, and thus prevents the imprint of any character in that denomination.

Depression of any of the numeral keys in the denominational row 190^b as the "6" key shown in dotted lines in Fig. 1, sets its stop 115 to arrest the advance of the rack 310, and limit the distance through which the converging lever 311^a, link 515 1/8 and type-carrier 514 are lifted.

The length of strokes permitted the rack 310 and its connected parts by any of the stops 115 corresponding with the numeral keys in denomination 190^b is not sufficient to operate the special locking means which forms the subject matter of this invention.

When any of the special designation keys, such as the "Bal", "Net" or "3%" keys in denomination 190^b is depressed, to set its stop in the path of the rack 310, the latter is permitted a farther travel than when the numeral keys of the denomination are operated. The link 515 1/8 which connects the converging lever 311^a of this denomination with its type carrier 514, carries a post or wiper 557 1/8 which, owing to the additional travel permitted the rack when any of the special designation keys are depressed, is thereby contacted with the inclined or cam edge 515 3/8^a of a shifter link or driven member 515 3/8. The shifter is slidably supported on a cross rod 506 1/2 passing through a slot therein, and is pivotally secured by a spacing pin or connector 557 3/8 to a non-print hook or latch 518 7/8 journaled on a cross bar 501 1/2.

The upper end of this non-print hook lies in proximity to a detaining stud 557 1/4 projecting from the printing hammer 510 3/8 in the next adjacent denomination to the right, such printing hammer in the present instance being a part of the denominational train of row 190^a corresponding with the units digits of the days of the month.

A spring 780 connected to the shifter and the rod 506 1/2, presses the cam end of the shifter into the path of the wiper 557 1/8. The wiper travels along the cam 515 3/8^a of the shifter and forces the latter forwardly against the tension of the spring 780 to rock the non-print hook or lock to effective position, over the detaining stud 557 1/4 on the printing hammer 510 3/8, so that even when

its individual hammer latch 518 1/4 and the universal detainer 518 are released as heretofore explained, the hammer 510 3/8 is still held against operation, and no character is printed in such adjoining denomination.

The high point of the cam 515 3/8^a on the driven member 515 3/8 terminates in a straight face or dwell 515 3/8^b along which the wiper or drive member 557 1/8 moves in its extreme travel, to maintain the non-print hook in effective position.

As soon as the wiper 557 1/8 on its return, escapes past the cam 515 3/8^a, the spring 780 restores the hook to ineffective position and resets the shifter link 515 3/8 to idle position.

A stationary guide 515 5/8 extends parallel with the path of travel of the wiper and is spaced apart from the cam end of the shifter a sufficient distance to enable the wiper to just pass between the shifter and the guide, and maintains the wiper 557 1/8 in its path, against displacement due to its travel along the incline or cam 515 3/8^a, and the pressure of the restoring spring 780.

An auxiliary spring 580 1/8 may be connected to the wiper 557 1/8 to assist the usual drive spring 383 to overcome the friction between the wiper and the shifter 515 3/8.

By locating the cam 515 3/8 at different points in the path of travel of the wiper, the non-print latch may be controlled or rendered effective by a larger or smaller number of keys in the same denomination.

Furthermore, the non-print mechanism herein set forth is not restricted in its use to a statement machine, but may be applied to any style of key-set printing machine, to enable certain keys in one denomination to control the imprint of characters in one or more different denominations, while characters in the remaining denominations are printed.

As one result of this invention, it is possible to non-print in a denomination intermediate other denominations in which printing occurs.

Changes other than those referred to, may be made in the form and arrangement of the several parts without departing from the spirit and scope of this invention.

What I claim is:—

1. In a machine, the combination with a keyboard, including a plurality of keys arranged in denominational rows or sets; typecarriers for the respective rows of keys, each typecarrier equipped with types corresponding to the keys in its respective row, the keys operable to control the positions of the types relatively to the printing line; and a hammer for each typecarrier; of means controlled by certain of the keys to positively prevent type impressions in at least one denomination.

2. In a machine, the combination with a keyboard, the numeral keys of which are arranged in denominations; printing mechanism, controlled by the numeral keys, and including type carriers arranged in corresponding denominations; and hammers to coöperate with the types of the respective type carriers; of non-print means controlled by keys in one denomination to prevent the imprint of characters in another denomination.

3. In a machine, the combination with a keyboard, the numeral keys of which are arranged in denominations; printing mechanism, controlled by the numeral keys, and including type carriers arranged in corresponding denominations, and hammers to coöperate with the types of the respective type carriers; of non-print means controlled by keys in one denomination to lock the printing hammer of at least one other denomination against operation.

4. In a machine, the combination with a keyboard, the numeral keys of which are arranged in denominations; printing mechanism, controlled by the numeral keys, and including type carriers arranged in corresponding denominations; and hammers to coöperate with the types of the respective type carriers; of means controlled by keys in one denomination and automatically effective upon the operation of the machine, to lock a printing hammer of another denomination in idle position.

5. In a machine, the combination with a keyboard, including a plurality of keys arranged in denominational rows or sets; type carriers for the respective rows of keys, each typecarrier equipped with types corresponding to the keys in its respective row, the keys operable to control the positions of the types relatively to the printing line; and a hammer for each typecarrier; of non-print means to positively prevent type impressions in at least one denomination, and means under the control of one of the regular keys in another denomination to shift the non-print means to effective position.

6. In a machine, the combination with a keyboard, the numeral keys of which are arranged in denominations; printing mechanism, controlled by the numeral keys, and including type carriers arranged in corresponding denominations; and hammers to coöperate with the types of the respective type carriers; of means effective only when certain keys of one denomination are operated, to prevent the imprint of characters in another denomination, the characters corresponding to the operated keys of the first-named denomination being printed.

7. In a machine, the combination with a keyboard having denominational rows of keys; type carriers and types for the corresponding denominations; printing ham-

mers for the type carriers; and drive mechanisms for the respective type carriers, the excursions of which drive mechanisms are controlled by the keys in the respective denominations; of means operable by one of the drive mechanisms at a predetermined point in its path, to prevent printing in another denomination.

8. In a machine, the combination with a keyboard having denominational rows of keys; type carriers and types for the corresponding denominations; printing hammers for the type carriers; and drive mechanisms for the respective type carriers, the excursions of which drive mechanisms are controlled by the keys in the respective denominations; of a lock operable by one of the drive mechanisms during a part of its travel, to prevent the operation of a printing hammer coacting with the types in a type carrier of another denomination.

9. In a machine, the combination with keys arranged in denominational rows; type carriers for the respective denominations, and bearing types corresponding with the several keys of such denominations; printing hammers to coact with the types in the respective type carriers; and drive mechanisms for the respective type carriers, the excursions of which are controlled by the keys of corresponding denominations; of non-print means controlled by certain only of the keys of one denomination to prevent the imprint of characters in another denomination.

10. In a machine, the combination with keys arranged in denominational rows; type carriers for the respective denominations, and bearing types corresponding with the several keys of such denominations; printing hammers to coact with the types in the respective type carriers; and drive mechanisms for the respective type carriers, the excursions of which are controlled by the keys of corresponding denominations; of means to eliminate printing in a denomination intermediate other denominations in which printing occurs, even though a key be depressed in such denomination wherein printing is eliminated.

11. In a machine, the combination with keys arranged in denominational rows; type carriers for the respective denominations, and bearing types corresponding with the several keys of such denominations; printing hammers to coact with the types in the respective type carriers; and drive mechanisms for the respective type carriers, the excursions of which are controlled by the keys of corresponding denominations; of means controlled by keys in one denomination to eliminate printing in another denomination intermediate remaining denominations in which printing occurs.

12. In a machine, the combination with

keys arranged in denominational rows; type carriers for the respective denominations, and bearing types corresponding with the several keys of such denominations; printing hammers to coact with the types in the respective type carriers; and drive mechanisms for the respective type carriers, the excursions of which are controlled by the keys of corresponding denominations; of a wiper mounted on the drive mechanism of one denomination; a shifter having a cam extending into the path of the wiper; a normally idle latch to which the shifter is connected; and a stud on one of the printing hammers, to be engaged by the latch to lock the hammer against operation.

13. In a machine, the combination with keys arranged in denominational rows; type carriers for the respective denominations, and bearing types corresponding with the several keys of such denominations; printing hammers to coact with the types in the respective type carriers; and drive mechanisms for the respective type carriers, the excursions of which are controlled by the keys of corresponding denominations; of a wiper mounted on the drive mechanism of one denomination; a shifter having a cam extending into the path of the wiper; a normally idle latch to which the shifter is connected; a stud on one of the printing hammers to be engaged by the latch to lock the hammer against operation; and a guide along which the wiper travels, to hold the wiper in its path against displacement.

14. In a machine, the combination with keys arranged in denominational rows; type carriers for the respective denominations, and bearing types corresponding with the several keys of such denominations; printing hammers to coact with the types in the respective type carriers; and drive mechanisms for the respective type carriers, the excursions of which are controlled by the keys of corresponding denominations; of a wiper mounted on the drive mechanism of one denomination; a shifter having a cam extending into the path of the wiper; a normally idle latch to which the shifter is connected; a stud on one of the printing hammers, to be engaged by the latch to lock the hammer against operation; and a spring to restore the shifter and latch to normal.

15. In a machine, the combination with keys arranged in denominational rows; type carriers for the respective denominations, and bearing types corresponding with the several keys of such denominations; printing hammers to coact with the types in the respective type carriers; and drive mechanisms for the respective type carriers, the excursions of which are controlled by the keys of corresponding denominations; of a wiper mounted on the drive mechanism of one denomination; a shifter having a cam ex-

tending into the path of the wiper; a normally idle latch to which the shifter is connected; a stud on one of the printing hammers, to be engaged by the latch to lock the hammer against operation; and a spring to overcome the resistance of the shifter to the travel of the drive mechanism.

16. In a machine, the combination with a series of denominational trains of mechanism, each train including keys, a position bar, a type carrier and a hammer to coact with the types in the type carrier; of means operable by one of the denominational trains of mechanism to prevent the printing of characters in another denomination.

17. In a machine, the combination with a keyboard having keys, and printing mechanism controlled by the numeral keys and including type carriers arranged in denominations; of means to eliminate printing in a denomination intermediate other denominations in which printing occurs even though a key be depressed in such denomination wherein printing is eliminated.

18. In a machine, the combination with a keyboard having keys, and printing mechanism controlled by the numeral keys and including type carriers arranged in denominations; of key-controlled means to eliminate printing in any denomination intermediate other denominations in which printing occurs even though a key be depressed in such denomination wherein printing is eliminated.

19. The combination with a keyboard, including a plurality of keys arranged in denominational rows or banks; typecarriers for the respective rows of keys, equipped with types corresponding to the keys in its respective row, the keys operable to control the positions of the types relatively to the printing line; and a hammer for each typecarrier; of automatic means to positively prevent printing in one denomination, said automatic means controlled by one of the regular denominational keys as an incident to its control of its correlated typecarrier.

20. In a machine, the combination with a keyboard, the numeral keys of which are arranged in denominations; printing mechanism controlled by the numeral keys, and including typecarriers arranged in corresponding denominations; and hammers to coöperate with the types of the respective typecarriers; of means controlled by keys in one denomination, and becoming effective automatically upon the operation of the machine, to prevent printing in another denomination.

21. In a machine, the combination with a keyboard, the numeral keys of which are arranged in denominations; printing mechanism controlled by the numeral keys, and including typecarriers arranged in corre-

sponding denominations; and hammers to coöperate with the types of the respective typecarriers; of denominational key controlled means operable coincidently with the operation of the machine, to positively prevent printing in another denomination even though keys are depressed in such last-named denomination.

22. In a machine, the combination with a keyboard, the numeral keys of which are arranged in denominations; printing mechanism controlled by the numeral keys, and including typecarriers arranged in corresponding denominations; and hammers to coöperate with the types of the respective typecarriers; of denominational key controlled means to positively prevent printing, in another denomination even though keys are depressed in such last-named denomination.

23. The combination with a series of denominationally arranged trains of mechanism, each train including a row of keys, stops set thereby, a positioning bar, whose excursions are limited by the key-set stops, a typecarrier connected with the positioning bar and having types corresponding with the keys of the particular train, and a hammer to coact with the types; of automatically operable means to prevent type impressions in at least one denomination, said automatically operable means being controlled by a key in one of said trains.

24. In a machine, the combination with a keyboard including a plurality of keys arranged in denominational rows or banks; a typecarrier for each row or bank of keys,

equipped with types corresponding to the keys in its correlated bank; and drive mechanisms for the several typecarriers, the excursions of the typecarriers in one direction being controlled by the keys; of non-print means controlled by one at least of the same keys, to prevent printing in one denomination, and operable as an incident to a print- 45 ing operation of the machine.

25. The combination with a series of denominationally arranged trains of mechanism, each train including a row of keys, stops set thereby, a positioning bar, whose excursions are limited by the key-set stops, a typecarrier connected with the positioning bar and having types corresponding with the keys of the particular train, and a hammer to coact with the types; of non-print 55 means automatically effective as an incident to the travel of one of the positioning bars past a predetermined point.

26. The combination with a series of denominationally arranged trains of mechanism, each train including a row of keys, stops set thereby, a positioning bar, whose excursions are limited by the key-set stops, a typecarrier connected with the positioning bar and having types corresponding 65 with the keys of the particular train, and a hammer to coact with the types; of non-print means; and an actuator controlled by one of the trains of denominationally arranged mechanism and effective to operate 70 the non-print means upon the travel of the typecarrier of such train to a predetermined point.

ARTHUR PENTECOST.
